DOOR RETAINER

Grover C. Turner, Oklahoma City, Okla.

Application October 18, 1937, Serial No. 169,704

2 Claims. (Cl. 292—278)

This invention appertains to new and useful improvements in closure controlling means.

The principal object of the present invention is to provide a door retaining mechanism whereby the door can be retained in closed or fully opened position against self-swinging.

Another important object of the invention is to provide a closure detent whereby the doors of a garage can be fully held in closed or automatically opened position, without manual assistance.

These and various other important objects and advantages of the invention will become apparent to the reader of the following specification.

In the drawings:

Figure 1 represents a top plan view of the mechanism attached to a pair of garage doors, showing the doors in open position.

Figure 2 is a top plan view of the mechanism showing the doors held in closed position.

Figure 3 is a fragmentary vertical sectional view showing the mechanism in closed door retaining position.

Figure 4 is a sectional view taken substantially on line 4—4 of Figure 2.

Figure 5 is a fragmentary detailed sectional view on the line 5—5 of Figure 1.

Referring to the drawings wherein like numerals designate like parts, it can be seen that numeral 5 denotes a garage structure which includes the doorway frame made up of the vertical side members *a—a* and the top frame member *b*. Numeral 6 denotes a beam secured to the horizontal member *b* and the upper ends of the side members *a—a* and to this is secured the forward portion of the retainer mechanism generally referred to by the numeral 7. The garage doors are denoted by numerals 8—8 and each is provided with a lug 9 on its inner side. Inwardly connected to these lugs 9—9 on the forward ends of the elongated arms 10—10 which at their upper ends are pivotally connected by a trunnion 11 to the roller 12 which operates between the depending flanges of the parallel angleiron guides 13—13. The forward ends of these angleiron members 13—13 are secured to the intermediate portion of the beam 6 while the rear ends are connected to the intermediate portion of the substantially V-shaped brace member 14 which is apertured at its ends to receive securing means whereby the same can be secured by its ends to a suitable portion of the garage.

Extending laterally from one of the angle-irons 13 are the angleiron guide members 15—15

between which rides the roller 16, said roller having upwardly and downwardly extending spindles 17—18 pivotally connecting the adjacent end of the links 19—20 to the roller 16, while the remaining ends of these links 19—20 are pivotally connected to the upper and lower ends of the aforementioned roller 12. A coiled extensible spring 21 has one end secured to one of the angleirons 13 while its opposite end connects to the roller 16. A bar 22 extends rearwardly from the beam 6 and connects the remaining ends of the angleirons 15—15.

It can now be seen that the spring 21 in Figure 2 is operative to hold the roller 12 toward the rear end of the guide members 13—13 and in so doing is holding the doors 8—8 in closed position.

In moving the doors 8—8 to open position, the doors are pulled open and as this occurs the arms 10—10 move forwardly on the roller 12 which moves the forward ends of the links 19—20 laterally of the guides 13—13. As the roller 12 passes the guides 15—15 the doors can be released as the tension of the spring 21 will snap the doors to fully opened position as the roller 12 is forced toward the forward ends of the guide members 13—13, carrying with it the arms 10—10. Thus, the doors 8—8 are held either in closed position as shown in Figure 2 under tension, or in fully opened position as shown in Figure 1, under the tension of the spring 21.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A door retainer of the character described comprising a swingable door mounted in a doorway, a guide extending at right angles to the doorway, a lateral guide extending from the first mentioned guide, an arm extending from the door and having one end slidably engaged with the first mentioned guide, a link member having one end engaged with the end of the arm engaged in the first mentioned guideway, the remaining end of the link being slidably connected with the second mentioned guide, and spring means normally tending to urge the last mentioned end of the link toward the first mentioned guide.

2. A door retainer of the character described comprising a swingable door mounted in a doorway

way, a guide extending at right angles to the doorway, a lateral guide extending from the first mentioned guide, an arm extending from the door and having one end slidably engaged with the first mentioned guide, a link member having one end engaged with the end of the arm engaged in the first mentioned guideway, the re-

maining end of the link being slidably connected with the second mentioned guide, and spring means connecting the last mentioned end of the link to the first mentioned guide, and supporting means for the said guide. 5
